(57) **CLAIM**

The ornamental design for a chainsaw, as shown and described.

DESCRIPTION

FIG. 1 is an isometric view of the chainsaw showing my new design;

FIG. 2 is a front view of the chainsaw shown in FIG. 1;

FIG. 3 is a rear view of the chainsaw shown in FIG. 1;

FIG. 4 is a side view of the chainsaw shown in FIG. 1;

FIG. 5 is another side view of the chainsaw shown in FIG. 1;

FIG. 6 is a top view of the chainsaw shown in FIG. 1;

FIG. 7 is a bottom view of the chainsaw shown in FIG. 1;

and,

FIG. 8 is another isometric view of the chainsaw of FIG. 1.

1 Claim, 8 Drawing Sheets# US D1,074,363 S
